JAMES C. WOODSON, OF EAST PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed June 23, 1925. Serial No. 38,980.

My invention relates to electric furnaces and particularly to resistor-supporting means therefor.

An object of my invention is to provide a relatively simple and easily removable resistor-supporting member for an electric furnace.

In practicing my invention, I provide a metal member located in a wall of the furnace and having a plurality of openings therein and hanger blocks having an end portion extending into an opening and interlocked with the metal member. A spacing member, of electric-insulating material, is located on the hanger block and aids in supporting the same in proper operative position.

In the single sheet of drawings,

Fig. 1 is a view in vertical longitudinal section of an electric furnace embodying my invention,

Fig. 2 is a fragmentary view in rear elevation of a device embodying my invention.

Fig. 3 is a view in vertical lateral section therethrough taken on the line III—III of Fig. 2,

Fig. 4 is a view, in front elevation, of a spacer member,

Fig. 5 is a view, in side elevation, of a hanger block,

Fig. 6 is a view, in rear elevation, of a hanger block,

Fig. 7 is a top plan view of a hanger block, and

Fig. 8 is a fragmentary view, in rear elevation, of a modified form of device embodying my invention.

An electric furnace 11 comprises the usual plurality of walls that may be built up of a plurality of bricks or blocks of heat-insulating and high-temperature-resisting refractory material usually employed in the art. The bricks or blocks are so arranged and disposed as to enclose a furnace chamber 13 of any suitable or desired contour and dimensions. As the particular construction and arrangement of the furnace walls forms no part of my invention, it is not illustrated or described in detail.

Each wall of the furnace structure that is to have associated therewith a resistor member is provided with a slot or groove 14 that may extend horizontally in the wall. A

metal member 15 of substantially channel-shape in lateral section, is located in the groove 14 with the laterally-extending members engaging the inner wall or bottom of the groove substantially as illustrated in Fig. 1 of the drawing. The depth of the groove 14 is such that the metal member 15 will be located below the surface of the wall for a purpose to be hereinafter set forth in detail.

The member 15 is provided with a plurality of symmetrically spaced openings 16 in the intermediate flange portion of the member, each of the openings 16 being of irregular contour. As illustrated particularly in Figs. 1 and 2 of the drawing, the opening 16 comprises a relatively large intermediate portion that is substantially circular in shape, and that has associated therewith two extensions 17 and 18, respectively, which may be located at an angle of substantially 45° from the central longitudinal axis of the member 15.

Integral portions 19 and 21, each of substantially Y-shape, are provided adjacent to the top and the bottom of each of the openings 16 in the member 15 and comprise lugs 20 or bosses of a suitable depth laterally of the member 15, the general proportions thereof being substantially as indicated in Figs. 2 and 3. The space between the two lugs of the members or portions 19 and 21 is substantially the same as that covered by the openings 17 and 18.

A plurality of hanger blocks 22, of refractory electric-insulating material severally comprise an elongated portion 23 that may be substantially circular in lateral section, and that is provided at the rear end portion thereof with two laterally extending lugs 24 and 25 that are located diametrically opposite thereon. The members 22 are further provided with a front end portion 26 that is somewhat larger, in lateral extent, than the portion 23, in order to prevent a resistor member, that is supported by the forward part of the portion 23 from being disengaged therefrom. The size or dimensions of the portion 23 and of the integral extensions 24 and 25 are such that they will fit into the opening 16 having extensions 17 and 18.

A spacer 27, of refractory electric-insulat-

ing material, is substantially square in section and is provided with an opening 28 there-in that has substantially the same irregular contour and that is of substantially the 5 same dimensions as was hereinbefore described in connection with the openings 16, 17 and 18.

The respective members 22 may have located thereon the spacer plates 27 by inserting the rear end portion thereof through the openings 28 before they are inserted 10 in the opening 16 in the member 15. In order to insert the hanger blocks, it is necessary to displace them angularly from their 15 normal operative position so that the lugs 24 and 25 will fit into the openings 17 and 18, when the hanger block may be moved longitudinally of its own axis into the opening 16. It is moved inwardly a sufficient 20 distance to permit the extensions 24 and 25 to clear the portions 19 and 21, after which the member is turned through an angle of substantially 45° or until the extensions 24 and 25 are aligned with the spaces between 25 the two lugs of the portions 19 and 21 after which the hanger block is moved forwardly so that the portions 24 and 25 fit into the space provided therefor, the normal operative position as seen from the rear being 30 shown more particularly in the lefthand end of Fig. 2 of the drawing.

In this position the inner block is interlocked with the member 15 of channel section, whereby any turning movement of the 35 hanger block relative to the member of channel section is effectually prevented. The spacer block 27 is then moved along the intermediate portion 23 of the hanger block until its inner surface operatively engages 40 or is closely adjacent to the outer surface of the central flange of the member 15. In this position, the weight of spacer member 27 is supported by the portion of the wall immediately adjacent to the groove 14 45 and the spacer member 27 is thereby made effective to support a portion or all of the weight of the hanger block and also of a resistor member 29 that is supported by the plurality of hanger blocks.

I have illustrated the resistor member as 50 being constituted by a ribbon of a suitable resistor material such as nichrome, that is bent to comprise a plurality of substantially parallel-extending loop portions, the resistor member being supported by having the upper ends of the respective loops located over the respective hanger blocks.

The length of the hanger blocks back of 55 the front part 26 and the thickness of the spacer member 27 located therein is such that the space therebetween is just sufficient to receive the resistor member 29. By this means, it is possible to maintain the hanger block in its interlocked position relatively to the member 15 of channel section, after the

hanger block has been moved into its normal operative position as was hereinbefore described.

Means for insuring that the bottom portions of the respective adjacent loops of the 70 resistor member shall not engage each other are constituted by refractory lugs or rods 31 that may be built to the furnace wall adjacent to the lower ends of the respective loops, substantially as illustrated in Fig. 1 75 of the drawing.

Fig. 8 illustrates a modified form of a hanger block 32, and of a member 33 of channel section. The member 33 is provided with a plurality of openings 34 there-through having substantially the same extensions as were hereinbefore described in connection with the openings 16 but these extensions are located in a direction substantially laterally of the member 33. The 80 integral lug portions 24 and 25, as were hereinbefore described for the hanger blocks 22, are located at a somewhat different angle in order that they may be located in a substantially horizontal plane when the hanger 85 block is in its normal operative position and interlocked with the member 33. The hanger block 32 at the left-hand end of Fig. 8 90 illustrates the extensions thereon in their normal operative positions and are shown as 95 interfitting with two longitudinally extending ribs 35 and 36 that extend between the spaced openings 34.

The hanger block 32 is inserted in substantially the same manner, that is, angularly displaced relative to its normal operative position, and is moved back far enough so that the lateral extensions on the member 32 will clear the integral ribs 37 and 38 of substantially Y-shape, after which the 100 hanger block may be turned through substantially 90° and be pulled forward to interlock the same. A spacer member 17 may be located on the respective hanger blocks 32 and will operate in substantially the same 105 manner as hereinbefore described in connection with the members 23. The ribs 35 and 36 serve also to strengthen the central flange 110 of the member 33 to counteract, to some degree, the weakening effect of the openings 34.

The device embodying my invention thus provides a hanger block that is easily and quickly inserted in and removed from its interlocked relation with a member of substantially channel-shape in lateral section, and that has associated therewith a spacer member that serves to support the hanger block. The hanger block is maintained in its normal operative and interlocked position relatively to the member of channel section by the resistor member.

While I have illustrated and described a specific embodiment of a hanger block and of a member of channel section, I do not 120

wish to be limited to the particular construction shown and described as departures may be made therefrom and all such modifications are intended to be covered by the appended claims which are to be limited only by the prior art.

I claim as my invention:

1. In an electric furnace, in combination, a member of substantially channel section, 10 and a hanger block for supporting a resistor member extending into said member of channel section and held in proper operative position therein by the resistor.

2. In an electric furnace, in combination, 15 a member of substantially channel section, and a hanger block for supporting a resistor member extending into said member of channel section and interlocked therewith, and held in said interlocked position 20 by the resistor.

3. In an electric furnace, in combination, 25 a member of substantially channel section having a plurality of openings therein, and hanger blocks for supporting a resistor member, and extending into said member through said openings and interlocked with said member of channel section.

4. In an electric furnace, in combination, 30 a member of substantially channel section having an opening therein, and a hanger block for a resistor member movable into said opening angularly displaced from its normal operative position, and interlocked with said member of channel section when 35 in its normal operative position therein.

5. In an electric furnace, in combination, 40 a member of substantially channel section having an opening therein, and a hanger block for a resistor member movable into said opening angularly displaced from its normal operative position, and interlocked with said member of channel section when in its normal operative position therein and held therein by the resistor member.

6. In an electric furnace, in combination, 45 a hanger block for supporting a resistor, a member located in a wall of said furnace having an opening therein for receiving an end portion of said hanger block, and lugs integral with said member for interfitting with said hanger block and preventing movement thereof relatively to said member.

7. In an electric furnace, in combination, 55 a hanger block for supporting a resistor, a member located in a wall of said furnace having an opening therein for receiving an end portion of said hanger block, and lugs integral with said member for interfitting with said hanger block and preventing movement thereof relatively to said member, said hanger block being held in said interfitting position by the resistor.

8. In an electric furnace, in combination,

a hanger block for supporting a resistor, 65 a member located in a wall of said furnace having an opening therein through which one end of said hanger block may be inserted when turned a predetermined angular amount from the normal operative position, 70 and lugs integral with the said member for interfitting with said hanger block when in its normal operative position.

9. In an electric furnace, in combination, 75 a hanger block for supporting a resistor, a member located in a wall of said furnace having an opening therein through which one end of said hanger block may be inserted when turned a predetermined angular amount from the normal operative position, 80 and lugs integral with the member for interfitting with said hanger block when in its normal operative position, said hanger block being held in said interfitting position by 85 the resistor.

10. In an electric furnace, in combination, 90 a member located in a wall of the furnace and having an opening therein, a hanger block, having a portion extending through said opening, for supporting a resistor member, and a spacing member, of refractory electric-insulating material, on said hanger block and having one face in operative engagement with the front face 95 of said member located in the furnace wall and co-operating with said wall to support said hanger block.

11. In an electric furnace, in combination, 100 a member located in a wall of the furnace and having an opening therethrough, a hanger block, having one end extending into the opening and interfitting with said member, for supporting a resistor member, and a spacing member of refractory electric-insulating material, located on said hanger block in operative engagement with one face 105 of said member located in the furnace wall and cooperating with the resistor to hold the hanger block in interfitting relation in said member. 110

12. In an electric furnace, in combination, 115 a member located in a wall of the furnace and having an opening therethrough, a hanger block, having one end extending into the opening and interfitting with said member, for supporting a resistor member, and a spacing member, of refractory electric-insulating material, located on said hanger block in operative engagement with one face of said member located in the furnace wall, co-operating with said wall to support said hanger block and cooperating with the resistor to hold the hanger block in interfitting relation in said member. 120

In testimony whereof, I have hereunto 125 subscribed my name this 11th day of June 1925.

JAMES C. WOODSON.
